UNITED STATES PATENT OFFICE.

JOHN ALBERT MANSS, OF CINCINNATI, OHIO.

DESIGN FOR A BOOTEE.

SPECIFICATION forming part of Design No. 31,988, dated December 12, 1899.

Application filed July 3, 1899. Serial No. 722,768. Term of patent 7 years.

To all whom it may concern:

Be it known that I, JOHN ALBERT MANSS, a citizen of the United States, and a resident of Cincinnati, in the county of Hamilton and State of Ohio, have invented a certain new and original Design for Bootees, of which the following is a specification.

In the drawing the figure is a perspective view of a bootee embodying my invention
10 preparatory to receiving a lacing-string.

The vamp is the same as of an ordinary lace-shoe. The front pieces have a tongue between them, and along each of their edges is a row of eyelets and lacing-hooks.

15 The lower parts of the back pieces resemble

those of a Congress gaiter, and between them and the front pieces are elastic gorings. The back pieces are extended upwardly and forwardly over the goring, and the front pieces meeting each other in front in a seam and in back in a similar seam, forming the top of the bootee, which has straps similar to those of an ordinary boot.

What I claim is—

The design for a bootee, substantially as shown and described.

JOHN ALBERT MANSS.
